STRAP FASTENING TOOL

Michael J. McAneny, Hillsboro, N. Mex.

Application April 18, 1945, Serial No. 589,011

6 Claims. (Cl. 81—9.1)

1

My present invention relates to a tool for drawing a flexible strap around hoses, casings, boxes, or other objects, and for fastening the strap to a buckle.

One of the principal objects of this invention is to provide a tool of this class whereby a flexible binding strap may be effectively and quickly drawn or tightened around a hose, box, or other object, by successive operation of the tool, so that any length of strap or any amount of take-up of the strap may be easily and quickly effected.

An important object of this invention is the provision of a tool of this class whereby the length of the stroke of the ratchet operation may be easily and quickly changed.

A further important object of this invention is to provide a tool of this class having a novelly constructed head for both holding or clamping the buckle of the strap fastening means and for yieldably but tightly gripping or clamping the strap in the desired adjusted position with respect to the buckle.

Another important object of this invention is to provide novel and efficient jaw means for drawing the strap through the buckle and for quickly releasing the strap for taking another bite or grip upon the strap in order to effect another tightening stroke.

A further important object of this invention is to provide a novel shearing means for cutting or shearing the strap to the desired length and also for forming the end of the strap.

A still further important object of this invention is to provide a combination shearing and forming means in connection with a strap tightening means whereby the strap may be sheared and formed after being drawn sufficiently tight.

Still another important object of this invention is to provide novel means for folding the end or sheared portion of the strap into a holding buckle.

An important object also of this invention is to provide a tool of this class which is particularly small, light of weight, and one which is easy to handle and easy to operate.

With these and other objects in view, as will appear hereinafter, I have devised a strap fastening tool having certain novel features of construction, combination, and arrangement of parts and portions, as will be hereinafter described in detail and particularly set forth in the appended claims, reference being had to the accompanying drawings, and to the characters of reference thereon, which form a part of this application, in which:

2

Fig. 1 is a fragmentary top view of my strap-fastening tool in a preferred form;

Fig. 2 is a fragmentary side elevational view thereof, showing by dotted lines the moved position of certain members;

Fig. 3 is an enlarged fragmentary end view thereof taken at 3—3 of Fig. 2;

Fig. 4 is a perspective view of the buckle and strap with one end of the strap cut and formed, ready to be folded into the buckle;

Fig. 5 is an enlarged fragmentary sectional elevational view thereof, taken through 5—5 of Fig. 1;

Fig. 6 is an enlarged fragmentary sectional view of the operating lever shown in an extended position, the section being taken substantially through 6—6 of Fig. 2;

Fig. 7 is an enlarged fragmentary sectional view thereof, taken through 7—7 of Fig. 1;

Fig. 8 is an enlarged fragmentary sectional view thereof, taken through 8—8 of Fig. 1;

Fig. 9 is a transverse sectional view thereof, taken through 9—9 of Fig. 8, showing the strap gripping jaws means on the slide;

Fig. 10 is a fragmentary side elevational view thereof, partly in section, showing a shifted position of the tool preparatory to shearing the end of the strap;

Fig. 11 is an enlarged transverse sectional view thereof, taken through 11—11 of Fig. 2, showing the strap shearing, forming and folding means;

Fig. 12 is an enlarged fragmentary view taken through 12—12 of Fig. 2, showing the inner side of the head;

Fig. 13 is a bottom view of the head portion of the tool; and

Fig. 14 is an enlarged fragmentary view of the operating lever shown in an extended position.

The hose clamp or stamp fastening means, shown fragmentarily in perspective in Fig. 4 consists of a sheet metal buckle A and a flexible band or strap B. One end B¹ of the strap is normally secured to the buckle before the band or strap is drawn around the hose or other article to be clamped. After the band or strap is drawn around such article, my tool is applied for drawing the band or strap tightly around the article and for securing the free end B² thereof in and to the buckle A.

My strap fastening tool, as shown in the drawings, is embodied in a single machine consisting essentially of a buckle holding head C, a strap tightening jaw means D, a strap cutting and forming unit E and a strap folding unit F.

The frame on which the several units are supported consists of a head member I of the head

unit C, a rear tie member 2, and longitudinal side members or bars 3 positioned at the opposite sides of the frame. The side members are secured at their opposite ends to the head and tie members by screws 4 and 5, respectively.

At the lower side of the head C is provided a buckle holding jaw means C¹ consisting of fixed jaws 1^a at the lower side and rear portion of the head member 1, and movable laterally spaced jaws 6^a at the lower end of the jaw member 6. The jaws 6^a are provided at the lower end of the jaw member 6, which is of inverted U-shape, the upper or cross-portion 6^b being pivotally connected by a pin 7 to the opposite lateral sides of the head member 1. The jaws 6^a are adapted to extend to the undersides of the side walls 1^b of the head member, as shown in Figs. 2 and 5.

The jaw member 6 is adapted to be rotated by a lever 8 pivotally mounted at the forward end and between the side walls 1^b of the member 1. This lever has a central cam 8^a and other cams 8^b at the opposite sides of the former. The cams 8^b perform a double function, namely that of opening the jaw means by rocking the jaw member 6 about its pivotal axis, when the lever 8 is raised to its dotted line position, shown in Fig. 5, and also for locking the jaws 6^a in closed position when the lever 8 is in its normal lowered position, shown by solid lines in Fig. 5. When opening the jaw, the cams 8^b are adapted to engage a lug 6^c extending upwardly from the jaw member 6 directly above its pivotal axis. When locking the jaws 6^a in closed position, the same cams 8^b engage shoulders 6^d at the upper and rear portions of the jaw member 6.

The jaws 1^a and 6^a are adapted to clamp the buckle A, and these jaws are so designed, by beveling the jaws, that when the head is placed over the buckle, the jaws are adapted to pick up the buckle, raise and clamp the same between the jaws when the lever 8 is depressed.

When the strap is drawn around the article to be clamped, the end B² thereof is threaded through the buckle A below a pawl 9 which is pivotally mounted at its upper end on a pin 7, on the head 1, but between the legs of the jaw member 6. The lower end of the pawl has transverse serrations 9^a which are adapted to grip the strap B² from the top side above the buckle A. The pawl 9 is normally urged forwardly at its lower free end, about its pivotal axis by a spring 11. The cam 8^a, above mentioned is adapted to engage a lug 9^b extending forwardly from the upper and pivoted portion of the pawl, and is thereby adapted to rock the pawl about its pivotal axis against the action of the spring 11 when the lever 8 is raised, for raising the serrated free end of the pawl above the strap B to permit the latter to be drawn freely through the buckle A. It will be here noted that the serrated portion of the pawl is spiral or eccentric with respect to its pivotal axis so that it is forced against the strap by the spring 11, whereby that the pawl is more tightly forced against the strap as the latter is attempted to be withdrawn from the buckle.

The strap tightening jaw means is carried in a slide 12 which is slidably carried at its opposite sides on the bars 3. The lower portion of the slide is provided with a horizontal slot 12^a cut into one side of the slide. The free end of the strap B² is adapted to extend from the buckle A through this slot, as indicated by dotted lines in Fig. 8. The jaw means consists of a serrated jaw or pawl member 13 which is pivotally mounted on the forward end of a jaw or pawl carrier or

support 14 pivotally mounted in a central vertical opening 12^b of the slide 12 and mounted, by a pin 18, on the opposite side walls forming the opening. At the upper portion of the slide is positioned a lever 15, the lower portion of which is pivotally mounted, by a pin 15^a, at the upper portion of the opposite side walls of the slide and within the opening 12^b.

The slide 12 is moved forwardly and backwardly on the frame by means of an operating lever 16 having at one end a longitudinally slotted portion 16^a which is pivotally mounted at its end on the upper portion of the rear tie member 2. The intermediate or slotted portion 16^a of the operating lever 16 is connected to the intermediate portion of the lever 15 by a link 17. The slide 12 is moved forwardly on the frame by rocking the operating lever 16 forwardly, the link 17 engaging the upper portion of the rear wall 12^c of the slide, within a recess 12^d, for limiting the rocking movement of the lever 15, thereby resulting in the forward movement of the slide. Such movement of the lever 15 about its pivotal axis also causes pivotal movement of the jaw carrier 14. The lower end of the lever 15 is extended slightly beyond its pivotal axis, as indicated by 15^b, and this extended end engages a recess portion 14^a in the jaw carrier, thereby slightly rocking the jaw carrier about its pivotal axis on the pin 18. When the slide is moved forwardly, the lower end of the lever 15 rotates the jaw carrier in a clockwise direction, raising the jaw member 13 from the strap B. As the slide 12 is drawn backwardly, the lower end of the lever 15 rotates the jaw carrier in the opposite, or counter-clockwise, direction tending to force the strap B against the wall 12^c forming the lower wall of the slot 12^a. Since the jaw member 13 is eccentrically mounted on its pivotal axis, backward drawing of the slide 12 causes the jaw member 13 to be progressively more tightly forced against the strap B, and the strap against the lower wall 12^c of the slide, thereby drawing the strap B with the slide through the buckle A, the pawl 9 being pivotally mounted to swing out of engagement with the strap to permit movement of the strap B in such direction.

On the forward end of the slide is reciprocally mounted in a vertical direction the cutter or shear member 21, this shear member being slidably secured to the front side of the slide 12 by plates 22. A compression spring 23 normally urges the shear member in a raised position with its shear or cutting portion 21^a at the lower end, raised substantially free of the slot 12^a, so as not to interfere with the drawing of the strap B through the slot. The lower wall 12^c of the slide 12 has a shearing edge 12^f cooperating with the shearing edge 21^a of the shear member for cutting the surplus end from the strap B after it is tightened about the article to be clamped.

On the upper free end of the lever 15 is a pivotal extension 24 which is adapted to be manually shifted to the solid line position, shown in Fig. 8, so that the free end of this extension may engage a recessed portion 21^b at the upper end of the shear member when the lever 15 is forced to its forward position.

On the lower end of the shear member 21 is provided a forming portion 21^c, the lower end of which is adapted to be forced below the upper side of the forward end of the wall 12^c of the slide 12, thereby bending upwardly the portion of the strap or band between the sheared-off end

and the forward end of the wall 12^c , this upwardly bent portion being designated B^3 in Fig. 4.

Thus the initial downward movement of the shear member is adapted to shear the end of the strap B , and continuous downward movement of the shear member forms the end, as stated.

The forward movement of the slide 12 is limited by a stop 25 on the head 1 so as to position the cutting or shearing means a short distance, which in this instance may be about $\frac{1}{2}$ inch from or beyond the buckle A .

It will be here noted that the pivotal connection of the rear end of the link 17 to the operating lever 16 may be changed to either the upper solid line position shown in Fig. 2, or the lower position shown by dotted lines, and designated 17 , in Fig. 2, or an intermediate position. It will be further noted that such various connections of the link 17 to the slotted portion 16^a of the operating lever 16 may be employed for drawing the strap B through the buckle. Progressively more leverage may be applied to the operating lever 16 , and consequently greater pulling force applied to the strap B , as the rear end of the link 17 is connected nearer the pivotal mounting of the lever 16 . It will however be noted that operation of the shear member 21 for shearing and forming the strap B may be effected by the lever 16 and link 17 when connected only as shown by solid lines in Fig. 2.

The pivotal connection between the link 17 and the operating lever 16 may be quickly changed by reason of the connection shown in Fig. 6. The slotted portion of the operating lever 16 has spaced enlarged circular recesses 16^b . The operating lever 16 and the link 17 are connected by a pivot screw 26 , the shank 26^a extending through the slot 16^a , and the head 26^b being positioned in one of the circular recesses 16^b . The end of the shank 26^a is reduced, as indicated by 26^c and over this reduced end is secured a cup nut 27 . Within the cup of the nut and against the link 17 is a compression spring 28 . The inner end of this cup nut may extend into a recess 17^a concentric with the hole for the shank of the pivot screw.

The cup nut 27 may be depressed against the action of the spring 28 , ejecting the head 26^b from the recess 16^b , and thereby permitting the shank of the pivot screw 26 to be moved within the slot 16^a until the head 26^b is moved opposite another desired circular recess 16^b within the operating lever 16 .

After the end of the strap B is formed with the tongue B^3 , it is in condition to be folded into the buckle A by forcing the free end of the strap between the edge of the folded over portion A^1 of the buckle and the arched portion A^2 thereof, or as shown in detail in my copending application, Serial No. 568,577, filed December 18, 1944, now abandoned.

This folding of the free end of the strap B into the buckle is effected by a folding device provided at the forward end of the slide. This folding device, as shown in the drawings, is in the form of a folding member 31 which is pivotally mounted on the forward end of the slide member 12 . The folding member 31 may be of U-shape, the ends of the legs 31^a being pivotally mounted at the opposite sides of the slide, inwardly from the bars 3 , and above the slot 12^a of the slide. On one of the legs 31^a of the folding member is provided a lever 32 for manually moving the folding member about its pivotal axis to either the operative or folding position, shown by dotted lines, or the out-of-the-way

position, shown by solid lines in Fig. 2. The connecting or cross-portion 31^b of the member 31 contains the folding portion of the member. The upper edge of the cross-portion 31^b is bevelled forwardly and downwardly as indicated by 31^c , and the lower portion of the front edge is also bevelled as indicated by 31^d . When the folding member 31 is in the position shown by dotted lines in Fig. 2, forward movement of the slide by the forward shifting of the operating lever 16 causes the upwardly bent end of the strap to be engaged by the bevelled portion 31^c and raised thereby. At the forward portion of its movement the cross-portion 31^b of the folding member is forced below a shoulder 1^c on the head member. Continuous forward movement of the folding member causes continuous raising of the free end of the strap, and the bending thereof about the near edge of the buckle, causing the free end of the strap to be forced below the arched portion A^2 of the buckle. The bevelled portion 31^d of the folding member then comes into action, forcing the free end of the strap below the arched portion A^2 and at the same time compressing the free end of the strap against the turned over portion A^1 and also pressing the arch portion A^2 tightly over the free end of the strap.

The slide is then withdrawn and the buckle 1 released by raising the lever 8 .

The forward position of the slide 12 , when folding the end of the strap B^3 under the arched portion A^2 of the buckle A , is, in this instance, forwardly of the shearing position of the slide. The stop 25 may therefore be pivoted on the rear or connecting wall 1^c of the head member, which wall provides the aforementioned shoulder 1^c . When the folding member 31 is lowered to the dotted line position of Fig. 2, and the slide 12 is moved forwardly, the member 31 will raise the stop 25 so that the member 31 may move under the shoulder 1^c . The pivotal stop 25 may be bifurcated so as not to interfere with either the forward die portion of the slide or the die portion 21^c of the shear member. The stop 25 may fall to its normal stop position by gravity when the slide 12 is withdrawn.

The folding member 31 is normally carried in a raised out-of-the-way position in front of the slide 12 . As shown, the shear member 21 has a transverse recess 21^d at its forward side for receiving the cross-portion 31^b of the folding member. The folding member is shifted from the solid line position to the dotted line or operative position when the slide is withdrawn. A spring or other suitable member (not shown), may be provided adjacent the pivotal axis of the folding member 31 for holding the same at either end in out-of-the-way or in operative positions.

The operating lever, shown in Fig. 14, is made telescopic, consisting of an outer tube 16^b and an inner rod 16^c . The tube has a pin 16^d which extends into a longitudinal slot 16^e in the rod. The slot may have transverse portions or recesses at its ends (only the recess at the outer end of the slot being shown) for locking the rod in either of its extreme positions.

While operation of the tool appears clear from the foregoing description, the operation is briefly described as follows: In connection with a strap passed around a package or the like and engaged with and passing through the buckle, the tool is laterally engaged with the strap which passes through the open slot in the slide. The head structure rear jaws are caused to engage the

rear buckle on each side of the strap, after which, the buckle clamping jaw is released to engage the forward side portions of the buckle and simultaneously the strap engaging panel is moved into engagement with the strap passing through the buckle. At this time the free end of the strap extends through the slide beneath the cutting, folding and sealing pivoted member on the slide; operation of the lever by a swinging movement causing the slide to reciprocate in the frame. By the construction described, the strap is clamped by the pivoted member against the bottom or anvil on the slide to pull or tension the strap through the buckle in one direction of movement of the slide, whereas, in the other direction of movement of the slide the strap is held in its drawn or tensioned position by the strap engaging pawl of the head, and the slide and pivoted member is free for movement to another clamping position with respect to the strap. Successive operation of the slide produces progressive tightening of the strap until the desired tightening is accomplished. When this is done, the manual control is shifted so that forward movement of the slide effects, first, a cutting of the strap to the desired end length, the forming thereof with an upward bend, and on further back and forth manipulation of the slide a folding and sealing of the strap into the buckle is obtained.

Though I have shown and described a particular construction, combination, and arrangement of parts and portions, I do not wish to be limited to the same, but desire to include in the scope of my invention the construction, combination, and arrangement substantially as set forth in the appended claims.

I claim:

1. In a strap fastening tool for fastening a strap to a buckle, a frame having a head with buckle and strap engaging means, a slide on the frame, an operating lever mechanism on the rear of the frame pivotally connected to the slide for reciprocating the same, the forward end of the slide having a shear portion, a shear member movably mounted on the slide to move at right angles to the direction of movement of the slide and adapted to engage the shear portion, and means connected with the lever mechanism for operating the shear member at one end of the stroke of the slide, the shear portion and the shear member having forming die portions in connection therewith for bending the sheared end of the strap upwardly by continued downward movement of the shear.

2. In a strap fastening tool for fastening a strap end to a buckle, a frame having a head with buckle and strap engaging means, a slide on the frame having an open slot to receive a strap extending through the slide, a lever mechanism on the frame pivotally connected to the slide for reciprocating the same, a shear member movably mounted on the slide to move at right angles to the direction of movement of the slide for shearing the strap in the slide, means on the lever for operating the shear member at the forward end of the stroke of the slide, a strap folding member pivotally mounted at the forward end of the slide, said folding member being normally located in an out-of-the-way position but shiftable downwardly about its pivotal axis forwardly of the slide, the forward end of the folding member being shaped for folding the sheared end of the strap over the buckle and of folding said end thereinto.

3. In a strap fastening tool for fastening a strap to a buckle, a frame having a head at one end, said head being provided with a buckle holding jaw at its rear portion, a movable jaw pivoted on the head in front of and in opposed relation to the rear jaw, cam means pivotally mounted on the head; engageable with the movable jaw, for closing the latter toward the rear jaw for clamping the buckle, a pawl pivoted on the head alongside the movable jaw, engageable by the cam means, and provided with a band-gripping portion at its lower end, said gripping portion being positioned above the jaws for gripping the band when the buckle is engaged by the jaws, resilient means for normally biasing said gripping portion forwardly for forcing the strap against the buckle, said cam means when reversed being capable of moving the pawl against the action of the resilient means for removing the gripping portion from the band when the jaws are open, said pawl being free to be moved against the action of the resilient means to allow the strap to be drawn past the pawl when the jaws are closed.
4. In a strap fastening tool for fastening a strap to a buckle, a frame having a head at one end, said head being provided with a buckle holding jaw at its rear portion, a movable jaw pivoted on the head in front of and in opposed relation to the rear jaw, cam means pivotally mounted on the head, engageable with the movable jaw, for closing the latter toward the rear jaw for clamping the buckle, a pawl pivoted on the head coaxially with the movable jaw, engageable by the cam means, and provided with a band-gripping portion at its lower end, said gripping portion being positioned above the jaws for gripping the band when the buckle is engaged by the jaws, resilient means for normally biasing said gripping portion forwardly for forcing the strap against the buckle, said cam means when reversed being capable of moving the pawl against the action of the resilient means for removing the gripping portion from the band when the jaws are open, said pawl being free to be moved against the action of the resilient means to allow the strap to be drawn past the pawl when the jaws are closed.
5. In a strap fastening tool for fastening a strap to a buckle, a frame having a head at one end, said head being provided with a buckle holding jaw at its rear portion, a movable jaw pivoted on the head in front of and in opposed relation to the rear jaw, cam means pivotally mounted on the head and provided with a cam portion, engageable with the movable jaw, for closing the latter toward the rear jaw for clamping the buckle, a pawl pivoted on the head alongside the movable jaw, and provided with a band-gripping portion at its lower end, said gripping portion being positioned above the jaws for gripping the band when the buckle is engaged by the jaws, resilient means for normally biasing said portion forwardly for forcing the strap against the buckle, said cam means having another cam portion for moving the pawl against the action of the resilient means for removing the gripping portion from the band when the jaws are open, said pawl being free to be moved against the action of the resilient means to allow the strap to be drawn past the pawl when the jaws are closed.
6. In a strap fastening tool for fastening a strap to a buckle, a frame having a head at one end, said head being provided with a buckle

holding jaw at its rear portion, a movable jaw pivoted on the head in front of and in opposed relation to the rear jaw, cam means pivotally mounted on the head and provided with a cam portion, engageable with the movable jaw, for closing the latter toward the rear jaw for clamping the buckle, a pawl pivoted on the head coaxially with the movable jaw, and provided with a band-gripping portion at its lower end, said gripping portion being positioned above the jaws for gripping the band when the buckle is engaged by the jaws, resilient means for normally biasing said portion forwardly for forcing the strap against the buckle, said cam means having another cam portion for moving the pawl against the action of the resilient means for removing the gripping portion from the band when the jaws are open, said pawl being free to be moved against the action of the resilient means to allow the strap to be drawn past the pawl when the jaws are closed.
